UNITED STATES PATENT OFFICE.

WILLIAM R. SMITH, OF BUFFALO, NEW YORK, ASSIGNOR OF ONE-HALF TO
HERBERT H. HEWITT, OF BUFFALO, NEW YORK.

MACHINE FOR FILLING FABRIC FOR TIRES.

No. 857,495.

Specification of Letters Patent.

Patented June 18, 1907.

Application filed November 18, 1906. Serial No. 343,724.

To all whom it may concern:

Be it known that I, WILLIAM R. SMITH, of Buffalo, in the county of Erie and State of New York, have invented certain new and useful Improvements in Machines for Filling Fabric for Tires, of which the following is a specification.

This invention relates to means for impregnating woven fabrics with a liquid or semi-liquid composition, such as a rubber solution, for the purpose of rendering the fabric waterproof, and improving its wearing qualities.

The invention has especial reference to apparatus for filling an annular fabric which is substantially U-shaped in cross section, and is prepared for use as the base or reinforcing portion of the shoe or tread member of a so-called clencher tire, the said shoe having flanges at its edges adapted to engage rigid flanges on a wheel rim, the shoe being formed to confine on the wheel rim an inflated air tube.

The invention consists in the improvements hereinafter described and claimed.

Of the accompanying drawings, forming a part of this specification,—Figure 1 represents a side elevation of a filling machine embodying my invention. Fig. 2 represents a section on line 2—2 of Fig. 1. Fig. 3 represents a fragmentary section on a larger scale through a different portion of the mold. Fig. 4 represents a transverse section of a completed tire shoe having a base or inner portion which is adapted to be filled by the improved apparatus.

The same letters of reference indicate the same parts in all the figures.

My improved apparatus comprises two mold members of annular form; viz., an outer member 12 and an inner member 13, said members being formed to create an annular space or mold cavity 14 corresponding in form to the annular fabric to be filled, the cavity in this case being adapted to contain and fit the outer and inner surfaces of a woven fabric 15 shaped to serve as the base or inner portion of a tire shoe which is formed in cross section as represented in Fig. 4, and is composed in part of the fabric base 15, and in part of a rubber tread portion 16 applied to the outer surface of the fabric base and vulcanized thereto. The apparatus of my

invention treats the fabric portion 16 before the tread portion is applied to it. The fabric base 15 is preferably thickened at its central portion by an increased number of plies formed at said portion to give the outer portion of the tire increased thickness and durability. The outer member 12 is made in two separable sections detachably secured together by bolts 17, as shown in Fig. 1, or by other suitable means, and is preferably adapted to be internally heated by steam or other heating agent. In the present case I have shown the member 16 provided with steam spaces or chambers 18, which are suitably connected so that steam admitted to one chamber through an inlet pipe 19 will circulate through the other chamber and pass therefrom through an outlet pipe 20, a suitable drip pipe 21 being provided for the escape of water of condensation from the lower portion of the lower chamber. The outer member 12 is provided with a suitable number of supply conduits 22 which conduct the filling composition from a suitable reservoir to the outer surface of the fabric 15. The inner member 12 is provided with a suitable number of conduits 23 which deliver the filling material to an annular chamber 24 formed in the inner member, said chamber having numerous radiating outlets 25 which deliver the material to the inner surface of the fabric 15. Suitable supply pipes are connected with the conduits 22 and 23, said pipes having flexible sections 26 which are sufficiently flexible to permit the relative movements of the mold members hereinafter described.

The outer member 12 is supported by a yoke 27, the central portion of which is mounted on a fixed vertical stud or bearing 28, the yoke and the outer member 12 being adapted to turn on said stud, which is provided with a shoulder 29 supporting the yoke and the member 12. The inner member 13 has a flat central or hub portion in which is formed an aperture which surrounds the stud 28, the said hub portion resting on a shoulder 30, which is preferably the upper end of a collar affixed to the stud 28. The collar 31, affixed to the stud 28 above the hub portion of the inner member 13, bears on the upper side of said hub portion, the inner member being adapted to turn between the said collars and upon the stud 28.

Mechanism is provided for turning the members 12 and 13 simultaneously in opposite directions, and for reversing the movement so that each member has a forward and 5 backward partial rotation, the movement of each being opposite that of the other. These movements of the members 12 and 13 distribute the filling material supplied by the conduits 22 and 23 over the outer and inner 10 surfaces of the fabric 15. The mechanism here shown for moving the mold members comprises two vertical rock shafts 32 journaled in fixed bearings, and resting on steps 33 at the bottom ends of the lower bearings. 15 Each rock shaft is provided with two oppositely-extending arms 34 35 at its upper end, the arms 34 projecting between studs 36 affixed to and projecting downwardly from the outer member 12, while the arms 35 project 20 between studs 37 affixed to and projecting downwardly from the inner member 13. To each rock shaft is affixed a lower arm 38, which is connected by a pitman 39 with an eccentric wrist pin 46 on a face plate 41 affixed to a driving shaft 42. The rotation of 25 the shaft 42 imparts a rocking movement through the pitman 39 to the rock shafts 32, and these impart forward and backward partial rotary motions to the mold members 12 and 13.

The operation of the apparatus is as follows: The upper section of the outer member 12 is raised from the lower section to permit the insertion of the fabric 15 in the lower section 30 of the member 12. The inner member 13 may be adapted to be raised to facilitate the location of the fabric in its proper place. The lower side of the fabric being properly located between the lower sides of the outer 35 and inner mold members, the upper section of the outer mold member is lowered to place, and properly locates the upper side of the fabric. The sections of the outer member 12 are then fastened together by the bolts 17, 40 and the filling composition is admitted through the several conduits, the said composition being forced into the conduits under a suitable degree of pressure by means not shown. The composition is thus supplied to 45 the outer and inner surfaces of the fabric, and caused to penetrate the same, the above-described motion imparted to the members 12 and 13 distributing the filling composition, and causing it to enter different portions of 50 the surfaces of the fabric. When the fabric has been suitably impregnated, the upper section of the outer member 12 is raised, and the fabric removed for subsequent treatment, including the addition to it of the tread 55 portion 16 and the vulcanization of said tread portion and of the filling composition. It will be seen that the inner mold member 13 is supported wholly outside the mold cavity, so that the said cavity is not obstructed in any way, and is open at all parts. 60

I claim:

1. A filling apparatus comprising an annular mold composed of an outer member and an inner member, said members having an annular cavity-forming faces, supporting means 70 for the inner member wholly outside the mold cavity, the latter being entirely unobstructed, and means for conducting filling material to the said cavity.

2. A filling apparatus comprising an annular mold composed of an outer member and an inner member, said members having an annular cavity-forming faces, means for conducting filling material to the said cavity, and means for moving said members to distribute the filling material. 75

3. A filling apparatus comprising an annular mold composed of an outer member and an inner member, said members having an annular cavity-forming faces, means for, conducting filling material through the members to the opposite faces thereof, and means for moving said members to distribute the filling material. 80

4. A filling apparatus comprising an annular mold composed of an outer member having separable sections, an inner member located between said sections, means for rotatively supporting said members, means for conducting filling material to the cavity 90 formed by said members, and means for rocking or oscillating the members.

5. A filling apparatus comprising an annular mold composed of an outer member having a yoke, and an inner member having a central hub, means for conducting filling material to the mold cavity, fixed bearings supporting the said yoke and hub, and means for 100 rocking or oscillating the members.

6. A filling apparatus comprising an annular mold composed of an outer member and an inner member, means for conducting filling material to the mold cavity, means for rotatively supporting said members, and means for 105 rocking or oscillating said members, comprising rock shafts having oppositely-projecting arms engaging ears affixed to said members, and means for rocking said rock shafts.

7. A filling apparatus comprising an annular mold composed of an inner member and an outer member, said mold having conduits for supplying filling material to the mold cavity, means for rocking or oscillating said members to distribute the filling material, 115 and a system of pipes for conducting the filling material to the conduits, said pipes having flexible sections.

In testimony whereof I have affixed my signature, in presence of two witnesses.

WILLIAM R. SMITH.
